UNITED STATES PATENT OFFICE

169,591

AUTOMOBILE HOOD ORNAMENT

Frederick A. Helm, Detroit, Mich., assignor to
Helm Accessories, Inc., Detroit, Mich., a corpora-
tion of Michigan

Application May 17, 1952, Serial No. 19,766

Term of patent 7 years

(Cl. D14—18)

To all whom it may concern:

Be it known that I, Frederick A. Helm, a citizen of the United States, residing at Detroit, State of Michigan, have invented a new, original, and ornamental Design for an Automobile Hood Ornament, of which the following is a specification, reference being had to the accompanying drawing, forming a part thereof.

Fig. 1 is a side elevational view of an automobile hood ornament showing my new design.

Fig. 2 is a top plan view thereof, and

Fig. 3 is a front elevational view thereof.

Fig. 4 is a horizontal sectional plan view, on approximately the plane indicated by the line 4—4 in Fig. 1, looking down.

I claim:

The ornamental design for an automobile hood ornament, as shown.

FREDERICK A. HELM.
